UNITED STATES PATENT OFFICE.

HARRY B. LYNCH, OF VERSAILLES, PENNSYLVANIA.

GALVANIZING-FURNACE.

SPECIFICATION forming part of Letters Patent No. 663,033, dated December 4, 1900.

Application filed June 2, 1899. Serial No. 719,059. (No model.)

To all whom it may concern:

Be it known that I, HARRY B. LYNCH, a resident of Versailles, in the county of Allegheny and State of Pennsylvania, have invented a new and useful Improvement in Galvanizing-Furnaces; and I do hereby declare the following to be a full, clear, and exact description thereof.

My invention relates to the heating of pots containing galvanizing or other metal used for coating. Its object is to provide a suitable furnace for work of this character in which generator or like low quality of fuel-gas can be used and in which provision is made for varying the heat in the furnace so as to properly heat the metal in the pot; for applying the heat to the upper part of the metal in the pot, so as to avoid, as far as possible, the making of dross, which comes from overheating of the metal; for quickly and rapidly cooling the pot, which is a necessity as soon as the coating is discontinued, such as at the end of a day's work, to prevent burning or oxidizing of the coating metal; for heating the incoming gases by the outgoing products and to some extent for heating the air supporting combustion; to provide access to any of the gas-flues, both for cleaning or burning out and in case the pot should burn through so that the spelter or other metal would run down into the gas-flues, and for quickly collecting and withdrawing such metal from the flues, a necessity especially in the employment of pots used for coating long pipe and bar where a very large body of metal must be employed.

The particular points of invention desired to be covered will be hereinafter described in detail and claimed.

To enable others skilled in the art to make and use my invention, I will describe the same more fully, referring to the accompanying drawings, in which—

Figure 1 is a horizontal section of the furnace and pot on the line 1 1, Fig. 2. Fig. 2 is in part a side view and in part a section, being made on the line 2 2, Fig. 1; and Figs. 3 and 4 are cross-sections on the lines 3 3 and 4 4, respectively, Fig. 1.

Like letters indicate like parts in each of the figures.

My invention is applied to the same class

of furnace as shown in Patent No. 419,695, granted upon my invention January 21, 1890, which provides for the use of natural gas or other high-heating gas; but the present furnace is constructed so as to utilize for heating a low-heating gas, generally known as "producer" or "generator" gas, which is formed continuously by the passage of air through a body of fuel and which requires different conditions for working from such rich gases as can be carried to the furnace in ordinary pipes.

The furnace shown is one suitable for the coating of pipe or bar and is therefore made of considerable length, the ordinary wrought-metal pipe being about eighteen to twenty feet in length and the furnace being made somewhat longer to provide for the proper handling of the pipe. While the pot is made comparatively long, it is narrow, as shown, though the pot illustrated is wider than the usual pots, because the pot A has a charging-section *a* and a withdrawing-section *b*, these sections being separated by a longitudinally-extending partition *c* entering from above part way into the metal of the pot, and the section *a* containing the sal-ammoniac or other like material through which it is considered desirable to introduce the pipe into the coating-bath. The pot A is formed of wrought metal in the usual way, and though it may contain peculiar mechanism for the handling of the pipe the same forms no part of the present invention and is not illustrated, the pot showing simply the inclined guide-bars *a'* from the charging-section into the withdrawing-section. The pot A rests upon the supporting-wall D, through which the waste-gas flue or flues *d* pass, it being preferred, for the proper working of the furnace and also to bring the same as close as practicable to the gas-flues, that the waste-gas flue shall be divided centrally into two sections *d* *d'* by the wall *d*². The waste-gas flue extends for the full length of the furnace. On each side of this waste-gas flue, separated therefrom by the walls *e*², are the gas-supply flues *e* *e'* or *f* *f'*. As illustrated in the drawings, these flues extend in from opposite ends of the furnace toward each other, the flues *e* and *f* being on one side of the furnace and meeting between the ends and being separated by

the wall e^3 , one flue being preferably shorter than the other, as shown, in the proper working of the furnace, and the flues $e' f'$ being on the other side of the furnace and located in like manner. It will be noted that these flues are open and that the bases thereof are inclined downwardly and outwardly toward the outer walls g of the furnace. Open flues are formed because of the liability of the pots to burn out and discharge the spelter or metal into the combustion-chambers, from which it will pass into these flues, and the inclined bases thereof provide means for tapping the metal from such flues and collecting it without the necessity of tearing down the entire furnace. For this purpose it will be noted that at intervals in the walls g are pockets or recesses g' , extending from the flues toward the outer face of the wall, into which such metal will naturally gather and from which it can be tapped by withdrawing the brick-work closing such pockets. The several gas-flues are controlled by suitable gas-valves f^2 , located at the ends of the furnace. The masonry inclosing the gas-flues and the waste-product flues extends up about on a line with the base of the pot, and extending longitudinally of the pot and from the base thereof up to the top thereof on each side are the series of combustion-chambers $h' k' k'$, these series of chambers corresponding in length and position to the gas-supply flues $e e' f f'$, respectively, the series $h k$ and $h' k'$, respectively, being separated by the walls h^3 , as shown in Fig. 1, while the individual chambers of each series are separated by the walls h^4 . Leading upwardly from the gas-supply flues and opening into the bases of the combustion-chambers are the gas-supply ports i , one for each combustion-chamber, while the air-ports l enter horizontally into the bases of the combustion-chambers, as shown in Fig. 3. It will be noted that to protect the base of the pot I form the tile sheathing i' , which deflects the gas upwardly toward the upper end of the combustion-chamber, the air passing over the top of the gas-flues and meeting the gas as it rises through the ports i and forming combustion in the chambers $h' k' k'$. The bases of the air-flues are flat, as shown, and supported in the same are the tiles i^2 in position to be slid over the gas-port i and close the same, so regulating the supply of gas from each port to the combustion-chamber. I prefer for the purpose of heating the incoming air to form along the sides of the furnace the air-chambers $m m'$, which are formed by means of the vertical walls m^2 , supported on pillars m^3 , upon which metal bar-supports m^4 rest, the tops of said chambers being closed by the tiles m^5 , resting on the walls m^2 and on brick-work projecting from the sides of the furnace. In this way the air enters between the pillars m^3 , rises in contact with the inner closing wall, absorbing heat therefrom before it enters the horizontal air-flues l . These air-flues themselves are, however, maintained at

considerable heat both by the initial combustion in the combustion-chambers and also by the gases in the escape-flues $p p' r r'$, into which the products pass from the combustion-chambers $h' k' k'$ through the flues p^2 . Where such outer air-chambers $m m'$ are employed, suitable ports m^6 are formed through the same to provide for adjusting the tiles i^2 over the gas-ports i , these ports m^6 being closed by blocks. The gas and air after meeting at the bases of the combustion-chambers is burned therein, and the flame and heated products travel upwardly along the pot and within the combustion-chambers, and thence through the ports p^2 into the longitudinally-extending escape-flues $p p' r r'$ above referred to. These flues are made of the same length as the respective gas-flues and series of combustion-flues above described, the chambers $p p' r r'$ being separated by the partition-walls h^3 , above referred to. In this way each particular section of the furnace is under the control of the operator through the valve f^2 , controlling the supply of gases thereto, and the heat of the pot can be regulated by the admission of more or less gas to each section, the gas passing from the gas-supply flue of each section into its combustion-chamber, and thence into its escape-flue. In this way the heat of the furnace may be maintained even or may be regulated so as to give greater heat in certain parts, as may be found desirable, according to the natural cooling of the coating metal by the incoming pipe or bar, the agitation of the metal in the insertion of the pipe and the handling of the same within the bath all affecting the relative heat of the metal, so that it is important to provide for regulation of such heat. A further important advantage is found in the fact that if one section is out of order the other three sections may be utilized to keep up the heat and provide for the running of the pot, though of course not as perfectly as where the heat can be regulated as above described.

It will be noted that at each end of the furnace is the transverse escape-flue s or s' , extending for the full width of the furnace, the escape-flues $p p'$ opening into the flue s and the escape-flues $r r'$ opening into the flue s' . These flues s and s' communicate by down-take-openings into the waste-product flue or tunnel d , and the waste products from the flues $p p'$ enter the flue s' and travel forward under the pot and for its entire length traveling through the tunnels or ports $d' d^2$ or the single tunnel d in contact with the partition-walls e^2 , separating the same from the gas-flues and serving in this way to heat the incoming gases, such waste products then passing to the stack T . For the proper heating and working of the furnace it is found desirable that the sections of the tunnel d shall be controlled so as to throw greater or less heat into contact with one or the other gas-flue, and for this purpose the partition-wall

d^3 between the two flues d' d^2 is carried longitudinally and centrally across below the flue s , as shown particularly at t in Fig. 4, the upper end of said wall being preferably spread so as to support the tile-plate t' , which can be adjusted from side to side, so as to close the port t^2 or t^3 , leading from said cross-flue s down into the tunnel-flues d' or d^2 . It will also be noticed that the end walls a^3 of the pot are exposed to the heat within the cross-flues s or s' . This is important in providing for maintaining the heat at the ends of the pots, where on account of the handling of the pipe the metal is liable to be cooled. In this way a high heat can always be maintained at the end portions of the pot and the chilling action of the metal consequent to its agitation be overcome.

When the furnace is in operation, the incoming gas enters the gas flues or tunnels e f e' f' and rises through the ports i , meeting the air entering through the air-ports l and burning in the bases of the combustion-chambers h k h' k' , rising therein in contact with the pot-walls, and thence passing horizontally into the flues p r p' r' , through which they pass to the end or cross flues s or s' and into the waste-product tunnel or tunnels, the heated products from the cross-flue s traveling forward through the same in contact with the dividing-walls e^2 between the same and the gas-flue, so as to heat the incoming gas. In this way it is found that the necessary heat for these galvanizing or like pots can be maintained without any further heating of the producer-gas and that the heat of the pot can be regulated so that the metal can be kept in perfect condition for working while the heat is not so high as to rapidly burn through the walls of the pot and destroy the same, a difficulty found in the heating of these pots with rich gas and which must be carefully guarded against. The heat can also be regulated in the different sections, as above described, so that the metal is maintained in as nearly perfect condition as possible for coating, while the metal at the ends of the pot is also heated through the exposure of the end portions thereof within the end or cross flues. Practical use has shown it desirable that the rear sections supplied with gas from the flues e e' shall be made longer than those supplied with gas from the flues f f' on account of the peculiar working of the pot and the necessity of maintaining the withdrawing end somewhat hotter than the other end.

A very important point in the operation of these furnaces is to prevent the drossing of the metal in rapid working of the furnace where a large tonnage is coated per day. It is necessary in so working to maintain the metal quite hot, keeping it cool by the rapid passing of the pipe through the same, the pipe absorbing the heat from the metal, it being found that the pipe must be raised to a certain temperature before the coating metal will permanently unite therewith. One great

difficulty with this way of working, however, is that where the furnace is run at such high heat as to keep the metal hot enough for this rapid work as soon as the coating operation is discontinued the furnace will overheat the metal in the pot and lead to very serious loss in drossing or oxidizing. The present furnace has great advantages in overcoming such difficulties, as the operator need only close off the gas-supply and open the stack wide, when the draft or suction of the same will draw the air in through the air-chambers m m' and the air-flues l into the combustion-chambers and into contact with the pot, so providing for the rapid cooling down of the pot the instant that the gas-supply is cut off.

What I claim as my invention, and desire to secure by Letters Patent, is—

1. A furnace for galvanizing and like pots having longitudinally-extending gas-supply flues on each side of and below the level of the pot, combustion-chambers on each side of the pot and extending up the walls thereof, outlet-flues extending longitudinally of the pot outside of the combustion-chambers, and gas-ports leading from the gas-supply flues vertically into the combustion-chambers and air-supply ports leading horizontally into the same, substantially as set forth.

2. A furnace for galvanizing and like pots, having longitudinally-extending gas-supply flues on each side of and below the level of the pot, combustion-chambers on each side of the pot and extending up the walls thereof, outlet-flues extending longitudinally of the pot outside of the combustion-chambers, gas-ports leading from the gas-supply flues vertically into the combustion-chambers and air-supply ports leading horizontally into the same, and sliding tiles in the air-ports for regulating the gas-ports, substantially as set forth.

3. A furnace for galvanizing and like pots, having longitudinally-extending gas-supply flues on each side of and below the level of the pot, combustion-chambers on each side of the pot and extending up the walls thereof, outlet-flues extending longitudinally of the pot outside of the combustion-chambers, gas-ports leading from the gas-supply flues vertically into the combustion-chambers and air-supply ports leading horizontally into the same, a cross-port at the end of the furnace with which the outlet-ports communicate and a tunnel escape-flue extending longitudinally under the pot, substantially as set forth.

4. A furnace for galvanizing and like pots, having a substructure supporting the pot provided with a longitudinally-extending waste-product tunnel under the same and longitudinally-extending gas-flues on each side of said tunnel, combustion-chambers on each side of the pot, gas-ports leading from the gas-flues upwardly into the combustion-chambers, and flues connecting the combustion-chambers with the waste-product tunnel, substantially as set forth.

5. A furnace for galvanizing or like pots, having a substructure supporting the pot and provided with gas-flues extending longitudinally thereof and having floors inclined outwardly and downwardly, combustion-chambers extending along the sides of the pot and gas-supply ports leading upwardly from the gas-flues into said combustion-chambers, substantially as set forth. 60
10. 6. A furnace for galvanizing or like pots, having a substructure supporting the pot and provided with gas-flues extending longitudinally thereof and having floors inclined outwardly and downwardly, combustion-chambers extending along the sides of the pot, gas-supply ports leading upwardly from the gas-flues into said combustion-chambers, and pockets in the gas-flues extending part way through the side walls, substantially as set forth. 65
15. 7. A furnace for galvanizing and like pots, having gas-supply flues on each side of and below the level of the pot, combustion-chambers on each side of the pot and extending up the walls thereof, outlet-flues extending longitudinally of the pot outside of the combustion-chambers, gas-ports leading from the gas-supply flues vertically into the combustion-chambers and air-supply ports leading 70
20. horizontally into the same, and air-chambers extending longitudinally of the furnace outside the gas-supply flues and communicating with the air-ports, substantially as set forth. 75
25. 8. A furnace for galvanizing or like pots, having on each side thereof below the level of the same, longitudinal gas-supply flues, each extending part way of the length of the furnace, combustion-chambers extending along the sides of the pot, ports leading from 80
30. the respective gas-supply flues vertically into said combustion-chambers, and longitudinally-extending outlet-flues outside the combustion-chambers and communicating therewith, each gas-supply flue having its own combustion-chambers and outlet-flue, substantially as set forth. 85
35. 9. A furnace for galvanizing or like pots, having longitudinally-extending gas-supply flues below the level of the pot and extending part way of its length, combustion-chambers extending along the sides of the pot, ports leading from the gas-supply flues into the respective combustion-chambers, air-ports leading horizontally into the combustion-chambers, longitudinally-extending outlet-flues with which the respective combustion- 90
40. chambers communicate, an escape-tunnel, and cross-flues communicating with the outlet-flues and opening downwardly into the escape-tunnel, substantially as set forth. 95
45. 10. A furnace for galvanizing or like pots, having longitudinally-extending gas-supply flues below the level of the pot, combustion-chambers extending along the sides of the pot, ports leading from the gas-supply flues 100
50. into the combustion-chambers, longitudinally-extending outlet-flues outside the combustion-chambers with which they communicate, an escape-tunnel, and a cross-flue communicating with the outlet-flues and opening downwardly into the escape-tunnel, the end wall of the pot being exposed within such cross-flue, substantially as set forth. 105
55. 11. A furnace for galvanizing or like pots, having longitudinally-extending gas-supply flues e, e' below the level of the pot, and extending part way of its length, combustion-chambers h, h' extending along the sides of the pot, ports i , leading from each gas-supply flue into the respective combustion-chambers, air-ports l , longitudinally-extending outlet-flues p, p' with which the respective combustion-chambers communicate, a waste-product tunnel extending longitudinally under the pot, and a cross-flue s , communicating with the outlet-flues and opening downwardly into the waste-product tunnel, substantially as set forth. 110
12. A furnace for galvanizing or like pots, having longitudinally-extending gas-supply flues below the level of the pot, combustion-chambers extending along the sides of the pot, ports leading from the gas-supply flues into the combustion-chambers, longitudinally-extending outlet-flues with which the respective combustion-chambers communicate, a waste-product tunnel extending longitudinally under the pot, a cross-flue communicating with the outlet-flues and opening downwardly into the waste-product tunnel, the wall d^3 dividing the waste-product tunnel into two sections and having the portion t extending under the cross-flue, and the deflecting-plate t' supported on the wall t , substantially as set forth. 115

In testimony whereof I, the said HARRY B. LYNCH, have hereunto set my hand.
